CLAIM

I claim the ornamental design for a swing exerciser, as shown.

DESCRIPTION

FIG. 1 is a perspective view of a swing exerciser showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

1 Claim, 7 Drawing Sheets
